Glendale, Ariz. 85301
Filed Apr. 21, 1967, Ser. No. 632,799
1 Claim. (Cl. 280—47.26)

ABSTRACT OF THE DISCLOSURE

A light wheel barrow including a body formed from a blank of sheet material and provided with a reinforcing flange, a wheel axle adjustable toward the front and rear of the vehicle body, and an adjustable handle member.

The present invention, while relating to hand operated push and/or pull vehicles in general, has more particular reference to a relatively lightweight, easily manipulated two-wheel barrow intended primarily for use to mix small amounts of mortar, cement or plaster in home gardening, lawn care and otherwise as a general utility conveyor for family and neighborhood use.

Another object of the present invention is the provision of a wheel barrow of the character and for the purposes set forth as distinguished from and more readily handled than the well-known rugged type of wheel barrow employed in ground excavation, building construction and like heavy work.

A further object of the invention is to provide what I term a handy-barrow or cart in which the material container or body member is integrally formed by punch press or otherwise cut from a sheet of thin, preferably 18 gauge, sheet steel.

And, a still further object of the invention is to provide a wheelbarrow of but few parts, inexpensive to manufacture, rigid and durable in construction and having novel adjustable features as will be described.

Other objects and advantages of the invention will become apparent from a consideration of the following detailed description taken in connection with the accompanying drawing wherein a satisfactory embodiment of the invention is shown.

In the drawing:

FIGURE 1 is a plan view of the punch-pressed or otherwise cut blank which forms the body of the vehicle, dash lines indicating the lines along which the blank is to be folded.

FIGURE 2 is a top plan view of the invention.

FIGURE 3 is a side view of the invention illustrated in FIGURE 1.

FIGURE 4 is a sectional detail taken on line 4—4 of FIGURE 2. And, FIGURE 5 is a sectional detail on line 5—5 of FIGURE 3.

In the drawing like numerals refer to similar parts throughout the several views.

The blank, indicated generally by numeral 6, FIGURE 1, is stamped or otherwise cut from a sheet of relatively thin metal, preferably steel, and when folded along the dash lines in the manner now to be described will constitute the body or material carrying container of the vehicle.

This blank 6 includes similar side portions 7 and 7' which, when folded along the lines 8 and 8', respectively, form the side walls of the body 6. The longitudinally extended rectangular center portion 9 of the blank forms the bottom and, respectively, front and rear upwardly

2

curved end walls 10 and 11. It will be observed that the diverging end edges of the side portions 7 and 7' are curved to coincide with the full line extensions of lines 8 and 8' when the end portions 10 and 11 are 5 rounded.

The longitudinal edges of the sides 7 and 7' and those of the end portions 10 and 11 are parallel and, when the blank is folded, the curved edges of the sides 7 and 7' engage the side edges of end portions 10 and 11 in overlapping relation which permits them to be integrally joined by spot welding or other means as rivets.

Parallel with the horizontal edges of the sides 7 and 7' are two fold lines 12 and 13 and in like relation to 15 the transverse end edges of the blank portions 10 and 11 are fold lines 14 and 15.

In forming the vehicle body, the parts 7 and 7', 10 and 11, are first doubled upon themselves by a 180° fold along the lines 12 and 14. Then, along a median 20 plane indicated by the lines 13 and 15, these two-ply portions, see FIGURE 4, are turned outward 90° thus forming a two-ply right angle reinforcing flange 16 around the perimeter of the vehicle body. Angle plates 17 welded to the under surface of this flange 16 provide an additional strengthening of the flange 16 at its corners.

To the bottom 9 of the vehicle body along its side edges, and secured thereto by screws 19 are elongated pieces 20, preferably of hard wood, which provide a mounting for the transversely extending axle 21. These 30 members 20 have a plurality of longitudinally spaced axle receiving openings 22 corresponding ones of which are axially aligned and thus provide means whereby the position of the axle 21, forward or back with respect to the vehicle body, may be changed to suit the operator. 35 Side wheels 18 support the vehicle, these wheels preferably having rubber tires and ball bearings, the latter, not shown, being carried on the protruding ends of the axle 21.

A handle for pushing and/or pulling the wheelbarrow 40 straddles the rear end of the material carrying container or body. In the illustrated embodiment of the invention this handle is U-shaped and constructed of tubular electrical conduit. The connecting intermediate portion of the handle provides a hand-grip 23 while the side arms 45 24, angularly disposed, are secured for longitudinal adjustment in bearing blocks 25 attached as shown by bolts 26 to the side walls 7 and 7' of the barrow.

It is believed that from the foregoing the objectives and construction of the invention have been made sufficiently clear as to call for no further explanation.

What I claim is:

1. In a wheel barrow, a sheet metal blank comprising an elongated rectangular center portion and a pair of like side portions having curved end edges diverging from said center portion with the longitudinal edges of the side portions and those of the center portion being parallel, the said blank being folded to form a rectangular open top container consisting of a horizontal bottom, 55 vertically extending parallel side walls and rounded end walls, the curvature of the end walls and corresponding curved end edges of the side walls engaging in overlapping relation, the resultant top edges of said end portions and those of said side walls being first doubled upon themselves to form two-ply vertical marginal portions, the said marginal portions then being folded along 60 a median plane to form an outwardly turned two-ply marginal flange surrounding the said container, said wheel 65

barrow including a transversely extending axle, means on the bottom of said container for supporting said axle, a pair of wheels rotatable on said axle in proximity to the sides of the container, a U-shaped handle including rearwardly extending, upwardly inclined side arms and a hand grip connecting portion, and means rigidly attached to the sides of said container in which the free ends of said side arms are secured, said axle supporting means comprising elongated blocks of wood having a plurality of axle receiving openings whereby the axle is adjustable forward or toward the back of said container, the said handle being tubular, and the said means in which the handle side arms are secured being angularly disposed blocks permitting longitudinal adjustment of the said side arms.
